WILLIAM P. WHITLEY

BY *J. C. Carmel, ATT'y.*

UNITED STATES PATENT OFFICE.

WILLIAM P. WHITLEY, OF ST. LOUIS, MISSOURI.

BASE-BALL GLOVE.

1,045,231.

Specification of Letters Patent. Patented Nov. 26, 1912.

Application filed April 1, 1911. Serial No. 618,432.

To all whom it may concern:

Be it known that I, WILLIAM P. WHITLEY, a citizen of the United States, residing at 2215 Lucas avenue, St. Louis, Missouri, have 5 invented a certain new and useful Improvement in Base-Ball Gloves, of which the following is a full, clear, and exact description, such as will enable others skilled in the art to which it appertains to make and use the 10 same, reference being had to the accompanying drawings, forming part of this specification, in which—

Figure 1 is a front elevational view of my improved form of glove. Fig. 2 is a front 15 elevational view of a modified form of my improved glove. Fig. 3 is a detail section taken transversely through the finger end portion of the form of glove illustrated in Fig. 1. Fig. 4 is a detail section taken trans- 20 versely through the outer end portion of the form of glove illustrated in Fig. 2 and showing the connection between the outer portions of the second and third finger pockets.

This invention relates to new and useful 25 improvements in gloves used by base ball players and more particularly the gloves commonly used by the players occupying fielders' positions.

The object of my invention is to provide 30 a simple form of glove having a substantially one-piece palm section which is cut away between the inner portions of the fingers and which is provided with webs between the outer portions of the fingers which 35 webs are so constructed as to bend or fold rearwardly or toward the back of the fingers when the fingers on the hand of the wearer of the glove are brought together as in the act of catching and holding a ball.

40 In base ball fielders' gloves of the type to which my invention pertains, it is very desirable that the outer ends of the fingers of the glove be connected by webs which will prevent the fingers from opening or sepa- 45 rating when the glove and hand receive the impact of a swiftly moving ball, and for this reason webs are formed between the outer ends of the fingers of the glove to limit the spreading movement of the fingers of the 50 wearer of the glove. It is also particularly desirable that the palm portion of the glove be entirely free from ridges formed by the partial folding together of said palm portion of the glove during the action of catch- 55 ing a ball and to do away with the possibility of the forming of folds or ridges, I

propose to cut away the continuous palm portion of the glove between the inner portion of the fingers and to split the webs between the outer portion of the fingers and 60 bend the split edges rearwardly and unite said edges with seams on the back-sides of said edges in order that the webs will tend to fold or bend rearwardly when the fingers of the wearer of the glove are moved together, as in the act of catching a ball. 65

To the above purposes my invention consists in certain novel features of construction and arrangement of parts hereinafter more fully described and claimed. 70

Referring by numerals to the accompanying drawings, 1 designates the palm section of the glove which is preferably formed in one piece and said palm section is provided on one side with an extension which is 75 folded over to form the back of the little finger pocket, and on the opposite side the palm section is provided with a web 2, the end of which is attached to the thumb section 3, which latter is fitted into the thumb 80 opening 4 in the usual manner.

The back section of the glove is of the usual form and is provided with three finger sections 5, the edges of which are attached to the palm section 1, by rows of stitching 6. 85

Formed in the palm section 1 between the inner portions of fingers are slots or openings 8 and the webs of palm section 1 between the outer portions of the fingers are split lengthwise from the openings 8 to the 90 finger tip portion of the palm section, and the edges formed by thus splitting said webs are bent or folded rearwardly against one another and are united by rows of stitching 7. Thus the seams which unite the split 95 edges of the web portions between the outer ends of the fingers are on the rear side of palm portion 1, and as the fingers of the wearer of the glove are bent forwardly and brought together, as in the act of catching 100 the ball, the material forming web portions will tend to bend rearwardly, thereby projecting from the back of the glove between the outer portions of the fingers, thereby allowing the outer portions of the fingers 105 to come together to grasp the ball in an easy and natural manner and which effect can not be obtained where the webs between the finger portions bend forwardly and form ribs or folds in the palm section of the 110 glove.

By cutting away the palm section 1 be-

tween the inner portions of the fingers to form the openings 8, there is no material at these particular points to fold inwardly and thereby form ribs or folds to destroy the smooth surface of the palm section of the glove.

In Fig. 2, I have shown a modified form of glove wherein the palm section is provided with openings 9 between the inner portions of the fingers and the web between the second and third fingers is split as designated by 11, and the edges formed by splitting said web are bent rearwardly and united by a row of stitching, and the seam 10 thus formed on the back of this particular web portion is covered by a reinforcing piece 12 which is attached in any suitable manner to the rear side of said web portion. In this form of glove, a continuous row of stitching 15 unites the finger back section with the palm section.

A glove of my improved construction is comparatively simple, is particularly intended for base ball players occupying fielders' positions, and by cutting away narrow strips of material between the inner portions of the fingers of the palm section, and splitting the webs between the outer portions of the fingers, and bending the edges of said 20 split webs rearwardly, the formation of ribs or folds on the inner face of the palm section of the glove is avoided and thus the fingers on the hand of the wearer of the glove can be brought together and bent forward 25 without inconvenience during the act of catching the ball.

It will be readily understood that minor changes may be made in the arrangement, construction and combination of the elements of my improved glove without departing from the spirit of my invention, the scope of which is set forth in the appended claims.

I claim:

1. In a baseball glove, a one-piece palm section having lengthwise slits between the finger portions, the edges of the material adjacent to which slits are bent rearwardly, and means for uniting said rearwardly bent edges to each other.

2. In a baseball glove, a one-piece palm section, provided with openings between the inner portions of the fingers, and having lengthwise slits between the outer portions of the fingers, the edges of the material adjacent to which slits are bent rearwardly and means engaging said rearwardly bent edges for uniting the same to each other.

3. In a baseball glove, a one-piece palm section having portions between the finger sections bent rearwardly, and attaching means passing through said rearwardly bent portions on the rear side of said palm sections.

In testimony whereof I hereunto affix my signature in the presence of two witnesses, this 28th day of March, 1911.

WILLIAM P. WHITLEY.
